UNITED STATES PATENT OFFICE.

GEORGE FREDERIC HATTON, OF ST. LEONARDS-ON-SEA, ENGLAND.

KINEMATOGRAPHIC APPARATUS.

SPECIFICATION forming part of Letters Patent No. 713,876, dated November 18, 1902.

Application filed August 11, 1902. Serial No. 119,831. (No model.)

To all whom it may concern:

Be it known that I, GEORGE FREDERIC HATTON, a subject of the King of England, residing at St. Leonards-on-Sea, Sussex, England, § have invented certain new and useful Improvements in or Relating to Kinemato-graphic Apparatus, of which the following is a specification.

The present invention relates to kinemato-graphic apparatus, the object being to provide a machine which will successively change the sections of a kinemato-graphic film in a rapid and simple manner, the mechanism being entirely driven from one shaft without employing spur or other gear. The apparatus can be adapted either for taking or exhibiting kinemato-graphic pictures.

In the accompanying drawings, Figure 1 is a perspective view of the film-operating mechanism according to this invention, part of the casing being removed; and Fig. 2 is a transverse section of the apparatus on the line 2 2 of Fig. 1.

Like letters indicate like parts throughout the drawings.

Referring to the drawings, the casing A carries a film-spool B, from which passes a series of pictures, transparencies, or the like or a photographic film C, adapted to receive a series of pictures. The film C is fed into the apparatus at uniform speed by a constantly-rotating roller D, against which the film is pressed by a roller E. The roller D is formed on the axle F, and its circumference is arranged to be equal to the width of one picture-section, and thus one picture is passed through at each revolution of the axle F, which is driven by a pulley G through a belt J, passing around a driving-pulley H, having a handle H', or the shaft F may be driven in any other convenient manner.

The pressure-roller E is carried by a bell-crank lever E', pivoted at E², and is normally held against the film C by means of a spring E³, and in order to regulate the pressure of the roller E, and consequently the rate of feed of the film C, the tension of the spring E³ may be slightly altered by means of a pivoted lever E⁴, attached thereto.

The necessary intermittent movement of the film at the exhibiting or exposing point is effected by intermittently drawing or jerk-

ing the strip or film a distance corresponding to the width of a picture-section. The intermittent movement or jerk is accomplished 55 by a constantly-rotating arm K, carrying a gripper L, which is so guided that during a portion of its path it is in contact or engagement with the film C and imparts to the latter the necessary movement. The gripper L 60 engages the film at both edges and is provided with frictional gripping material L², which engages the film.

The guide comprises a rail M, suspended from the casing and arranged to lead the gripper L into and out of contact with the film at the necessary positions. The gripper L is pivoted to the arm K and carries a finger L', which is kept pressing against the guide-rail M by a spring K', having an adjusting-screw 65 K². The film having been guided past the exhibiting-point by suitable means passes over a friction-roller N, and the guide-rail M terminates a short distance on either side of the roller N, and the gripper L therefore leaves 70 the rail and presses the film C against the roller N and pulls the film through the guides to an amount approximately equal to the width of one picture-section. The guides for the film consist of metal plates O, between 75 which the film passes from the roller and by which it is brought into proximity with the roller N. The side of the guide-plates which is in contact with the emulsion on the film is cut away in the center in order that the metal 80 may not damage the pictures. At one end of the guide-rail a screwed rod P is provided having an adjusting-handle P', by means of which the distance during which the gripper 85 is in contact with the film can be adjusted. 90 Normally the film is just out of contact with the roller N, so that the roller may continuously rotate, owing to the impulses imparted to it by the gripper L, and that the film may only be in contact with the roller while a jerk 95 is taking place.

The film is more firmly held between the feed-rollers D E than it is by the gripper L, so that if the gripper be set to feed rather more than one picture the film will always be 100 drawn tight, and the gripper will then slip over the film slightly. This slip can be made as small as desired.

In order to keep the film in proper relation

to its guides, pads Q, carried on levers Q', may be kept pressing against the film by springs Q² or the like.

A lens is disposed in front of the exhibiting-point R, and in the case of a kinemato-graphic camera a suitable shutter is also provided. When the machine is employed as a lantern, the light may conveniently be reflected through the exhibiting-film by a mirror S, arranged at a convenient angle to the film.

What I claim as my invention, and desire to secure by Letters Patent, is—

1. In a kinemato-graphic apparatus the combination of a film having a series of pictures, a constantly-rotating feed-roller, a radial arm on the same axle as the roller and carrying a gripper which intermittently engages the film.

2. In a kinemato-graphic apparatus the combination of a film having a series of pictures, a roller which feeds one picture at each revolution, a radial arm on the same axle as the roller and carrying a gripper which intermittently engages the film.

25 3. In a kinemato-graphic apparatus the combination of a film having a series of pictures, a feed-roller, a radial arm on the same axle as the feed-roller, a movable gripper on the end of the arm and means for intermittently guiding the gripper into contact with the film.

4. In a kinemato-graphic apparatus the combination of a film having a series of pictures, a roller which feeds one picture at each revolution, a radial arm on the same axle as the feed-roller, a movable gripper on the end of the arm and means for intermittently guiding the gripper into contact with the film.

45 5. In a kinemato-graphic apparatus the combination of a film having a series of pictures, a roller which feeds one picture at each revolution, a radial arm on the same axle as the feed-roller, a movable gripper on the end of the arm and means for guiding the gripper into contact with the film for a distance rather more than the width of one picture-section.

6. In a kinemato-graphic apparatus the combination of a film having a series of pictures, a feed-roller, means for keeping the film in contact with the roller, a radial arm on the same axle as the feed-roller, a movable gripper on the end of the arm and means for guiding the gripper into contact with the film for a certain distance.

55 7. In a kinemato-graphic apparatus the combination of a film having a series of pictures, a roller which feeds one picture at each revolution, means for keeping the film in contact with the roller, a radial arm on the same axle as the feed-roller, a gripper pivoted to the end of the arm, means for guiding the gripper into contact with the film for a certain distance and a surface against which the gripper presses the film.

65 8. In a kinemato-graphic apparatus the combination of a film having a series of pictures, a roller which feeds one picture at each revolution,

lution, means for keeping the film in contact with the roller, means for varying the pressure on the film, a radial arm on the same axle as the feeding-roller, a gripper pivoted on the end of the arm, means for guiding the gripper into contact with the film for a certain distance and a surface against which the gripper presses the film.

9. In a kinemato-graphic apparatus the combination of a film having a series of pictures, a roller which feeds one picture at each revolution, means for keeping the film in contact with the roller, means for varying the pressure on the film, a radial arm on the same axle as the feed-roller, a gripper pivoted on the end of the arm, adjustable means for pressing the gripper out of alinement with the arm, means for guiding the gripper into contact with the film for a certain distance and a surface against which the gripper presses the film.

10. In a kinemato-graphic apparatus the combination of a film having a series of pictures, a roller which feeds one picture at each revolution, means for keeping the film in contact with the roller, means for varying the pressure on the film, a radial arm on the same axle as the feed-roller, a gripper pivoted on the end of the arm, adjustable means for pressing the gripper out of alinement with the arm, means for guiding the gripper into contact with the film for a certain distance, means for adjusting that distance and a surface against which the gripper presses the film.

11. In a kinemato-graphic apparatus the combination of a film having a series of pictures, a roller which feeds one picture at each revolution, means for keeping the film in contact with the roller, means for varying the pressure on the film, a radial arm on the same axle as the feed-roller, a gripper pivoted on the end of the arm, adjustable means for pressing the gripper out of alinement with the arm, means for guiding the gripper into contact with the film for a certain distance, means for adjusting that distance, a surface against which the gripper presses the film and means for guiding the film through the apparatus from the feed-roller to that surface.

12. In a kinemato-graphic apparatus the combination of a film having a series of pictures, a roller which feeds one picture at each revolution, means for keeping the film in contact with the roller, means for varying the pressure on the film, a radial arm on the same axle as the feed-roller, a gripper pivoted on the end of the arm, adjustable means for pressing the gripper out of alinement with the arm, means for guiding the gripper into contact with the film for a certain distance, means for adjusting that distance, a surface against which the gripper presses the film, means for guiding the film through the apparatus from the feed-roller to that surface and means for driving the axle of the feed-roller.

13. In a kinemato-graphic apparatus the

combination of a film having a series of pictures, a roller which feeds one picture at each revolution, means for keeping the film in contact with the roller, means for varying the

5 pressure on the film, a radial arm on the same axle as the feed-roller, a gripper pivoted on the end of the arm, adjustable means for pressing the gripper out of alignment with the arm, means for guiding the gripper into 10 contact with the film for a certain distance, means for adjusting that distance, a surface against which the gripper presses the film, means for guiding the film through the apparatus from the feed-roller to that surface, 15 means for driving the axle of the feed-roller, and means for supporting the unwound film in proper relation to the feed-roller.

14. In a kinematographic apparatus the combination of a casing, an axle bearing therein, a feeding-roller on the axle whose circumference is equal to one picture-section, a kinematographic film passing over the roller a radial arm mounted on the same axle as the feed-roller and a gripper on the arm which in- 25 termittently engages the film.

15. In a kinematographic apparatus the combination of a casing, an axle bearing therein, a feeding-roller whose circumference is equal to one picture-section, a kinematographic film passing over the roller, a radial arm mounted on the axle of the feed-roller, a gripper pivoted on the end of the arm and a rail supported in the casing to guide the gripper into contact with the film at certain positions. 35

16. In a kinematographic apparatus the combination of a casing, an axle bearing therein, a feeding-roller whose circumference is equal to one picture-section, a pressure-roller 40 supported in proximity to the feed-roller, a kinematographic film passing between the rollers, a radial arm mounted on the axle of the feed-roller, a gripper pivoted on the end of the arm and a rail supported in the casing 45 to guide the gripper into contact with the film at certain positions.

17. In a kinematographic apparatus the combination of a casing, an axle bearing therein, a feeding-roller whose circumference is 50 equal to one picture-section, a pressure-roller supported in proximity to the feed-roller, a kinematographic film passing between the rollers, a radial arm mounted on the axle of the feed-roller, a gripper pivoted on the end 55 of the arm, a rail supported in the casing to guide the gripper into contact with the film at certain positions and a roller against which the film is pressed by the gripper.

18. In a kinematographic apparatus the 60 combination of a casing, a feeding-roller whose circumference is equal to one picture-section, a pressure-roller supported in proximity to the feed-roller on a pivoted bell-crank lever, a spring attached to the bell- 65 crank lever to maintain the pressure of the roller, a kinematographic film passing between the rollers, a radial arm mounted on the axle

of the feed-roller, a gripper pivoted on the end of the arm, a rail supported in the casing to guide the gripper into contact with the film 70 at certain positions and a roller against which the film is pressed by the gripper.

19. In a kinematographic apparatus the combination of a casing, an axle bearing therein, a feeding-roller whose circumference 75 is equal to one picture-section, a pressure-roller supported in proximity to the feed-roller on a pivoted bell-crank lever, a spring attached to the bell-crank lever to maintain the pressure of the roller, a pivoted hand-lever attached to the spring by which its tension may be altered, a kinematographic film passing between the rollers, a radial arm mounted on the axle of the feed-roller, a gripper pivoted on the end of the arm, a rail supported in the casing to guide the gripper into contact with the film at certain positions and a roller against which the film is pressed by 80 the gripper.

20. In a kinematographic apparatus the 90 combination of a casing, an axle bearing therein, a feeding-roller whose circumference is equal to one picture-section, a pressure-roller supported in proximity to the feed-roller on a pivoted bell-crank lever, a spring 95 attached to the bell-crank lever to maintain the pressure of the roller, a pivoted hand-lever attached to the spring by which its tension may be altered, a kinematographic film passing between the rollers, a radial arm 100 mounted on the axle of the feed-roller, a gripper pivoted on the end of the arm, a spring on the arm engaging the gripper, an adjusting-screw for the spring on the arm, a rail supported in the casing to guide the gripper 105 into contact with the film at certain positions and a roller against which the film is pressed by the gripper.

21. In a kinematographic apparatus the combination with a casing, an axle bearing 110 therein, a feeding-roller whose circumference is equal to one picture-section, a pressure-roller supported in proximity to the feed-roller on a pivoted bell-crank lever, a spring 115 attached to the bell-crank lever to maintain the pressure of the roller, a pivoted hand-lever attached to the spring by which its tension may be altered, a kinematographic film passing between the rollers, a radial arm mounted on the axle of the feed-roller, a gripper pivoted on the end of the arm, a spring 120 on the arm engaging the gripper, an adjusting-screw for the spring on the arm, friction-surfaces on the gripper, a rail supported in the casing to guide the gripper into contact 125 with the film at certain positions and a roller against which the film is pressed by the gripper.

22. In a kinematographic apparatus the combination with a casing, an axle bearing 130 therein, a feeding-roller whose circumference is equal to one picture-section, a pressure-roller supported in proximity to the feed-roller on a pivoted bell-crank lever, a spring

- attached to the bell-crank lever to maintain the pressure of the roller, a pivoted hand-lever attached to the spring by which its tension may be altered a kinematographic film passing 5 between the rollers, a radial arm mounted on the axle of feed-roller a gripper pivoted on the end of the arm, a spring on the arm engaging the gripper, an adjusting-screw for the spring on the arm, friction-surfaces on the 10 gripper, a rail supported in the casing to guide the gripper into contact with the film at certain positions, a roller against which the film is pressed by the gripper and an adjustable rod forming a continuation of the rail.
- 15 23. In a kinematographic apparatus the combination with a casing, an axle bearing therein, a feeding-roller whose circumference is equal to one picture-section, a pressure-roller supported in proximity to the feed- 20 roller on a pivoted bell-crank lever, a spring attached to the bell-crank lever to maintain the pressure of the roller, a pivoted hand-lever attached to the spring by which its tension may be altered a kinematographic film passing 25 between the rollers, a radial arm mounted on the axle of feed-roller, a gripper pivoted on the end of the arm, a spring on the arm engaging the gripper, an adjusting-screw for the spring on the arm, friction-surfaces on the 30 gripper, a rail supported in the casing to guide the gripper into contact with the film at certain positions, a rail against which the film is pressed by the gripper, an adjustable rod forming a continuation of the rail and metal 35 guides over which the film passes cut away at the point where the emulsion carries a picture.
24. In a kinematographic apparatus the combination with a casing, an axle bearing 40 therein, a feeding-roller whose circumference is equal to one picture-section, a pressure-roller supported in proximity to the feed-roller on a pivoted bell-crank lever, a spring attached to the bell-crank lever to maintain 45 the pressure of the roller, a pivoted hand-lever attached to the spring by which its tension may be altered a kinematographic film passing between the rollers, a radial arm mounted on the axle of the feed-roller, a gripper pivoted 50 on the end of the arm, a spring on the arm engaging the gripper, an adjusting-screw for the spring on the arm, friction-surfaces on the gripper, a rail supported in the casing to guide the gripper into contact with the film at certain positions, a rail against 55 which the film is pressed by the gripper, an adjustable rod forming a continuation of the rail, metal guides over which the film passes cut away at the point where the emulsion carries a picture and spring-controlled pads which keep 60 the film in proper relation to the guides.

25. In a kinematographic apparatus the combination with a casing, an axle bearing therein, a feeding-roller whose circumference is equal to one picture-section, a pressure- 65 roller supported in proximity to the feed-roller on a pivoted bell-crank lever, a spring attached to the bell-crank lever to maintain the pressure of the roller, a pivoted hand-lever attached to the spring by which its tension 70 may be altered a kinematographic film passing between the rollers, a radial arm mounted on the axle of the feed-roller, a gripper pivoted on the end of the arm, a spring on the arm engaging the gripper, an adjusting-screw 75 for the spring on the arm, friction-surfaces on the gripper, a rail supported in the casing to guide the gripper into contact with the film at certain positions, a rail against which the film is pressed by the gripper, an adjustable rod forming a continuation of the rail, metal guides over which the film passes cut 80 away at the point where the emulsion carries a picture, spring-controlled pads which keep the film in proper relation to the guides, and 85 a pulley-and-belt gear to drive the axle of the feed-roller.

26. In a kinematographic apparatus the combination with a casing, an axle bearing therein, a feeding-roller whose circumference 90 is equal to one picture-section, a pressure-roller supported in proximity to the feed-roller on a pivoted bell-crank lever, a spring attached to the bell-crank lever to maintain the pressure of the roller, a pivoted hand-lever attached to the spring by which its tension 95 may be altered a kinematographic film passing between the rollers, a radial arm mounted on the axle of the feed-roller, a gripper pivoted on the end of the arm, a spring 100 on the arm engaging the gripper, an adjusting-screw for the spring on the arm, friction-surfaces on the gripper, a rail supported in the casing to guide the gripper into contact with the film at certain positions, a rail against 105 which the film is pressed by the gripper, an adjustable rod forming a continuation of the rail, metal guides over which the film passes cut away at the point where the emulsion carries a picture, spring-controlled pads which 110 keep the film in proper relation to the guides, a pulley-and-belt gearing to drive the axle of the feed-roller and a spool from which the film is fed.

In testimony whereof I have signed my 115 name to this specification in the presence of two subscribing witnesses.

GEORGE FREDERIC HATTON.
